United States Patent Office

Des. 212,652
Patented Nov. 5, 1968

212,652

TYPEWRITER OR THE LIKE

Gerhard Dietrich, Furth, Bavaria, and Alfred Mamet,
Altenberg, Nuremberg, Germany, assignors to Triumph
Werke Nuernberg A.G., Nuremberg, Germany

Filed Aug. 14, 1967, Ser. No. 8,881

Claims priority, application Germany Feb. 15, 1967

Term of patent 14 years

(Cl. D64—11)

FIG.1

FIG.2

FIG. 3

FIG. 4

FIG. 1 is a front perspective view of a typewriter showing our new design;

FIG. 2 is a front view;

FIG. 3 is a side view; and

FIG. 4 is a rear view thereof.

The essential features of our design reside in the portions shown in solid lines, conventional keys and other elements being shown in broken lines.

We claim:

The ornamental design for a typewriter or the like, substantially as shown and described.
